UNITED STATES PATENT OFFICE.

WILLIAM E. PEARSON, OF SAUGUS, ASSIGNOR TO NATHAN H. DANIELS, OF BOSTON, MASSACHUSETTS.

VALVE-GEAR FOR COMPOUND ENGINES.

SPECIFICATION forming part of Letters Patent No. 394,993, dated December 25, 1888.

Application filed November 26, 1887. Serial No. 256,215. (No model.)

To all whom it may concern:

Be it known that I, WILLIAM E. PEARSON, of Saugus, in the county of Essex and State of Massachusetts, have invented certain new 5 and useful Improvements in Valve-Gear for Compound Engines, of which the following is a specification.

My invention relates to steam-engines, and more particularly to the valve-gear of the 10 same, and has for its object to provide a simple mechanism to operate the valve of the second cylinder of the class of steam-engines known as "compound engines."

My invention consists in the combination, 15 with the usual valve-gear of a reciprocating engine, of an additional eccentric having a limited play on the crank-shaft of the engine, a connection between said eccentric and the valve of the second cylinder, and means 20 whereby said eccentric is converted by the rotation of the crank-shaft either into a forward or backing eccentric, and thus caused to operate the valve of the second cylinder in unison with that of the main cylinder whether 25 the crank-shaft is rotated forward or backward, as I will now proceed to describe.

Of the accompanying drawings, forming a part of this specification, Figure 1 represents 30 a side elevation of a ("tandem") compound engine embodying my improvements, the shaft of the same being shown in section. Fig. 2 represents a top plan view and partial section on the line $x-x$, Fig. 1. Fig. 3 represents a section on the line $x'-x'$, Fig. 1. Figs. 4 and 5 35 represent detail views, hereinafter referred to. Fig. 6 represents a diagrammatic view of the valve-gear of a "link-motion" engine in "full gear" forward and the relation thereto of my improvements, showing the cylinders 40 with the steam-chests removed. Fig. 7 represents a section on line $y-y$, Fig. 6, showing the position of valves, eccentrics, and pistons in Fig. 6. Fig. 8 represents a view of the 45 valve-gear represented in Fig. 6, as it appears in full gear back, showing the position of the eccentrics, valves, and pistons as opposite to that shown in Figs. 6 and 7. Fig. 9 represents also a detail view, which will be fully explained hereinafter.

50 It is well known that compound engines are intended for the more economical use of

steam by using two or more cylinders in connection, and exhausting the steam from the first or main cylinder into the second, and so on. In the present instance two cylinders are 55 shown arranged in "tandem fashion" and adapted to be worked so as to rotate the crank in both directions, forward and back. It is also well known that an engine adapted to run both ways is provided with two eccentrics—one for the advancing motion, and known as the "forward eccentric," and one for the backing motion, and called the "backing eccentric." These eccentrics are connected to a "link," so called, the forward eccentric 60 at the top and the backing eccentric at the bottom of the same. Motion is communicated to the valve by means of a rod connected to the same and leading to the link-block, which is movable in the link to vary the length of 65 stroke of the valve.

Heretofore it has been the custom to use a second set of eccentrics and links to operate the valve of the second cylinder. These devices render the construction and operation 75 of engines of this class complicated and expensive and occupy considerable space, so that their arrangement is oftentimes a difficult matter.

By my improvements I do away with the 80 necessity of duplicating eccentrics and links for operating the valve of the auxiliary or second engine, and substitute for the second set heretofore employed more simple and compact operating devices, all of which I will now 85 proceed to describe.

Of the drawings, a a' represent steam-cylinders of common construction, secured in any suitable manner so that they shall be in line, as shown in Figs. 1 and 2.

b represents the piston-rod, arranged in such manner as to pass through cylinder a and into cylinder a' , and constituting a single piston-rod for the two cylinders, the pistons b b' being secured to said rod in any suitable 95 manner. In the present instance I have attached the steam-chests c c' to the sides of the cylinders a a' , as the most convenient arrangement.

d represents the valve-rod which connects 100 the main valve g of cylinder a to the link-block d' . Said rod is pivotally connected to

said block, which is moved forward and back by the eccentrics $e e'$ through the eccentric-rod $f f'$ and link f^2 , the valve g being thus operated in the usual manner—that is to say, 5 when the link is adjusted by the usual devices, 4 5 6 7 8, herein described, to bring the rod f' of the forward eccentric into close proximity to the link-block d' , as shown in Fig. 6, a forward rotation is imparted to the 10 crank-shaft h' of the engine, and when the link is adjusted to bring the rod f' of the backing eccentric into the same relation with the link-block, as shown in Fig. 8, a backward rotation is imparted to the crank-shaft. 15 In carrying out my invention I have, instead of providing duplicates of the above-described devices as the means for operating the valve g' of the second cylinder, provided the simpler devices which I will now describe. 20 h represents an eccentric loosely fitted on shaft h' and adapted to turn easily thereon. (See Figs. 1, 2, 3, and 4.) On said eccentric is fitted a strap, h^2 , to which strap is secured an eccentric rod or "blade," h^3 . Said rod or 25 blade is connected at its outer end to a rod, h^4 , which rod extends to and enters the steam-chest c' at the forward or outer end of the same, Fig. 2, where it is connected with the valve g' , as shown in Figs. 6, 7, and 8. Eccentric h is provided with a projection, i , on one side, adapted to engage with a projection or offset, i' , on a collar, i^2 , surrounding shaft h' and secured thereto by set-screws or in any other suitable manner. The position of collar 35 i^2 upon the shaft is such that when the engine is moving forward said collar will correspond to the position of the forward eccentric, e , and the projection i' of the collar, coming into engagement with projection i on eccentric h , (the 40 same being loose on shaft h' ,) forces the eccentric h to conform to the position of the forward eccentric, e , and remain a forward-motion eccentric as long as the engine continues to move in that direction. The form of 45 collar i^2 and eccentric h and its projection i , and their operative relation to each other, can be best understood by reference to Figs. 3, 4, and 6.

The operation of the eccentric by collar i^2 50 thus far described has been forward, the valves of both cylinders opening and closing their respective ports exactly together, as will be seen by reference to Figs. 4 and 7, where the engine is represented as in full gear forward—that is, the piston at the forward end of the cylinders $a a'$ and valves $g g'$ have just 55 commenced to open ports $j j'$ to admit steam to the pistons $b b'$, the position of the link being such that the valve g gets full travel, 60 which can be varied after starting by raising said link, and thereby imparting to valve g a shorter travel, as will be well understood by all skilled in the use of link-motion engines.

Let it be supposed now that the engine is 65 moving forward and it is desired to reverse the direction of the movement. The position of the link will be changed to that shown in

Fig. 8 and the forward eccentric, e , will become inoperative or "out of gear," and the backing eccentric e' , which has heretofore 70 been inoperative while the engine has been in full gear forward, is brought into operative position with the link f' by its rod or blade being brought into line with link-block d' and imparts motion to the same, and through it to 75 the valve-rod d and valve g , movements which are the reverse of those produced by the adjustment shown in Figs. 6 and 7, thus causing the valve g to admit steam through the port j' and on the opposite side of the piston b' , as 80 shown in cylinder a , Fig. 8. The reverse movement having been given to valve g , the crank-shaft h' , on which eccentric h and collar i^2 are located, now rotates backwardly, as indicated by the arrow in Fig. 8, and of course 85 eccentric h , being loose on said shaft, as stated, will remain motionless in the position in which it is left by collar i^2 before the change of direction of motion of shaft h' until the shaft h' makes a little less than a half-revolution, 90 when collar i^2 engages projection i and carries eccentric h around, causing it to conform to the position of backing eccentric e' and become also a backing eccentric, operating 95 with the eccentric e' , so that both valves $g g'$ are worked backwardly in unison.

In Fig. 5 I have shown a different form of eccentric h , which, instead of having a projection, i , is provided with a cavity, k , which receives a feather secured to the shaft h' in 100 the same relation to the eccentrics $e e'$ as is collar i^2 . When the engine changes direction, the feather is carried around with the shaft h' and engages with the eccentric h , as shown 105 in Fig. 5.

The travel or movement of the valve g' in connection with eccentric h is what is termed "full travel"—that is, said valve being directly connected with the eccentric gets the full throw thereof. The benefit derived from 110 this arrangement is that the valve g' has full travel, and thus gives full opening to the ports $j j'$, so that the admission of steam to and its escape from cylinder a' is not varied, as it would be if valve g' were controlled by a link-motion, and thus back-pressure on the main 115 cylinder is avoided to a great extent.

I prefer to make the cylinder a' of larger area than main cylinder a for several reasons, the principal one being that when the engine 120 is being reversed the valve g' of the second cylinder remains motionless in position to prevent the escape of steam from said cylinder while the shaft is turning sufficiently to bring the collar i^2 into engagement with projection i , and back-pressure on the main piston will be lessened by the enlarged area in cylinder a' .

The link f^2 is operated by the usual devices (shown in Figs. 6 and 8)—viz., a saddle, 125 2, affixed to the link, having a pin, 3, to which is attached a lifter, 4, pivotally connected to an arm, 5, attached to a shaft, 6, and an arm, 7, also attached to said shaft, and a reach-rod,

8, pivotally connected to arm 7 at its outer end and having its inner end connected with a lever, (not shown,) whereby the link can be adjusted to any desired position and the travel of valve *g* regulated in the manner common in link-motion engines.

I do not limit myself to the use of the described devices for engaging the eccentric *h* to the shaft *h'* in the different positions described, and thereby causing it to become either a forward or a backing eccentric, as said devices may be variously modified without departing from the nature or spirit of my invention.

15 I claim—

1. In a compound engine, the combination, with the main cylinder, its valve, and a link-motion valve-gear therefor, of the second cylinder, a valve therefor, an eccentric, *h*, having a limited play on the crank-shaft of the engine and adapted to conform either to the forward or the backing eccentric of the main valve-gear, and a rod connecting said eccentric *h* and the valve of the second cylinder,

25 as set forth.

2. The combination of the valve *g*, its valve-

gear, the eccentric *h*, having a projection, *i*, strap *h²*, and rod or blade *h³*, the collar *i²*, affixed to the crank-shaft and having the projection *i'*, the valve *g'*, and the valve-rod *h⁴*, 30 connected thereto and to the eccentric-rod *h³*, whereby the valve *g'* is operated in unison with the main valve *g*, as set forth.

3. In a compound engine, the combination, with the main cylinder, its valve, and link-motion valve-gear, of the second cylinder, of larger area than the main cylinder, the valve *g'* of said second cylinder, the loose eccentric *h*, having a projection, *i*, the collar *i²*, affixed to the crank-shaft and having a projection, *i'*, 40 and the rods *h³ h⁴*, whereby the valve of the said second cylinder is operated in unison with the valve of the main cylinder, as set forth.

In testimony whereof I have signed my name 45 to this specification, in the presence of two subscribing witnesses, this 12th day of November, A. D. 1887.

WILLIAM E. PEARSON.
